UNITED STATES PATENT OFFICE.

THOMAS HARPER, OF UNION HILL, NEW JERSEY.

DESIGN FOR A LICENSE-PANEL BRACKET-ARM FOR AUTOMOBILES.

40,984.

Specification for Design.

Patented Nov. 8, 1910.

Application filed September 2, 1910. Serial No. 580,267. Term of patent 3½ years.

To all whom it may concern:

Be it known that I, THOMAS HARPER, a citizen of the United States, residing at Union Hill, in the county of Hudson and State of New Jersey, have invented a new, original, and ornamental Design for a License-Panel Bracket-Arm for Automobiles, of which the following is a specification, reference being had to the accompanying drawings, in which—

Figure 1 is a front elevation, Fig. 2 a

rear elevation, Fig. 3 a top view, and Fig. 4 an end view of a license-panel bracket-arm embodying my design.

I claim:

The ornamental design for a license-panel bracket-arm for automobiles, as shown.

THOMAS HARPER.
